Primary Examiner — Cynthia Ramirez*Assistant Examiner* — Michael A Maharajh(74) Attorney, Agent, or Firm — Benoit & Cote Inc.; C. Marc Benoit(57) CLAIM

We claim the ornamental design for a gaming machine cabinet, as shown and described.

DESCRIPTION

FIG. 1 is a perspective view of our ornamental design of the gaming machine cabinet;

FIG. 2 is a front view of the gaming machine cabinet of FIG. 1;

FIG. 3 is a right side view of the gaming machine cabinet of FIG. 1;

FIG. 4 is a left side view of the gaming machine cabinet of FIG. 1;

FIG. 5 is a top plan view of the gaming machine cabinet of FIG. 1;

FIG. 6 is a bottom plan view of the gaming machine cabinet of FIG. 1; and,

FIG. 7 is a rear view of the gaming machine cabinet of FIG. 1.

The broken lines in figures are for purpose of illustrating portions of the gaming machine cabinet which form no part of the claimed design.

1 Claim, 6 Drawing Sheets(56)
